UNITED STATES PATENT OFFICE

JOSEPH M. HALL, OF HAMILTON, ONTARIO, CANADA, ASSIGNOR TO UNIVERSAL DRAFT GEAR ATTACHMENT CO., A CORPORATION OF ILLINOIS

SHOCK ABSORBER

Application filed August 4, 1924. Serial No. 729,887.

This invention relates to that type of draft gears or shock absorbers which are more particularly designed for use on railway cars, and in which a plurality of sets of intercalated friction plates are employed which are adapted to slide lengthwise relatively to each other, and which are adapted to be pressed transversely against each other or to be released from each other in a transverse direction when applying and releasing the shock absorber.

One of the objects of this invention is to provide a shock absorber of high capacity which is more especially adapted for a railway draft rigging wherein a certain free release is obtained with a large friction area of its friction members and a low pressure per unit of friction area on the friction members, and thereby obtaining a smooth and graduated action of the parts.

Another object of this invention is to provide a mechanism of this character which embodies intercalated friction members which are substantially alike in construction and not attached to the usual followers of a draft rigging or other parts, thereby simplifying the construction as well as facilitating repairs and also making a construction which is very compact.

Another object of this invention is to organize the mechanism that when the same is in operation for absorbing the shock of the load, a practically uniform friction load will be applied, and the pressure at both ends of the main or thrust spring will be utilized for producing a pressure on the parts which are intended to frictionally engage each other and to release the same from each other.

A further object of this invention is to provide a draft gear of this character having the capacity of becoming practically solid when a load is applied to the same in excess of that for which the draft gear is designed, and thereby prevent such an "over-solid" load from injuring the absorber which "over-solid" limit is effected by means which are comparatively simple and inexpensive and unattached but supported on parts of the shock absorber, and thus serving to protect the friction elements from damage by shocks

which are in excess of the capacity for which the draft gear is intended.

In the accompanying drawings:

Figure 1 is a top plan view, partly in section, of my improved draft gear or shock absorber showing the same in a fully released or open position.

Figure 2 is a similar view in a fully closed position.

Figure 3 is a side elevation of my improved draft gear or shock absorber, partly in section, and showing the parts in fully released or open position corresponding to the position of the parts shown in Figure 1.

Figure 4 is a view similar to Figure 3 but showing the parts in a fully closed position corresponding to the position of the parts shown in Figure 2.

Figure 5 is a side elevation of one of the friction plates arranged at the side of one of the sets.

Figure 6 is an end view of the draft gear or shock absorber.

Figure 7 is a vertical cross section of the same, taken on line 7—7, Figure 1.

Figure 8 is a side elevation of one of the friction plates arranged in the middle part of one of the sets.

Figure 9 is an outer elevation of one of the thrust members or spring seats of the thrust spring.

Figure 10 is a top plan view of the same partly in section.

Figure 11 is a vertical cross section, taken on the correspondingly numbered line in Figure 2.

Figure 12 is an outer elevation of one of the thrust heads or wedge casings.

Figure 13 is a top plan view of the same partly in section.

Figure 14 is a side elevation of one of the wedge plates.

Figure 15 is a side edge view of the latter.

Similar characters of reference indicate like parts throughout the several views.

Inasmuch as the shock absorber forming the subject of this invention is symmetrical it is immaterial which end of the device is toward the end of the car, but in the following description, for convenience in explaining

the structure and operation of this device it may be assumed that the follower 16 is toward the end of the car and the follower 17 away from the same. In the following description a forward movement has been assumed to mean a movement in the direction which has the effect of setting up a shock resisting effect and a rearward movement is assumed to mean a return movement of the parts to their normal or relaxed position. The terms forward and backward are to be taken as synonymous with the inward and out so far as the movements of parts in the direction of the length of the shock absorber is concerned.

This draft gear or shock absorber is adapted to be mounted between two followers 16 and 17 arranged transversely in the usual and well-known manner between the longitudinal sills or beams of a car body, so that these followers are free to move one toward the other in a direction lengthwise of a car but the extent of the separation of the same being limited by the usual draft lugs or front stops and the buff lugs or back stops which are arranged on these sills which are engaged by the outer sides of these followers.

The shock absorber draft gear which embodies my invention is adapted to be mounted between these followers without being physically connected therewith and thereby permit this gear or absorber to be constructed as a complete unit and inserted as such between the followers when installing the same on a car and also removed therefrom as a unit for the purpose of making repairs.

This improved draft gear or shock absorber comprises two thrust heads or wedge casings 23, 24 which are preferably constructed of cast metal and arranged transversely between the car sills and engaged at their rear or outer sides with the front or inner sides of the followers 16 and 17, respectively. Each of these thrust heads is provided with a central opening 25 and on horizontally opposite sides of the front or inner end of this opening with front or inner inclined faces 26 which diverge forwardly or inwardly, as best shown in Figures 1 and 2.

Between the two thrust heads are arranged a plurality of longitudinal friction plates 27 which constitute two sets, the members of one set alternating with those of the other so that they are intercalated. The opposite ends of these two sets of friction plates are arranged within the central openings 25 of the two thrust heads and at times the rear ends of one of these sets of friction plates engage with the front or inner side of one of the followers and the rear or outer ends of the other set of friction plates engage with the front or inner side of the other follower so that these plates are compelled to move longitudinally forward or inward with the followers, while at other times the rear or outer ends of these

friction plates are spaced apart from the respective followers for a purpose which will presently appear. Each of these friction plates is provided on the rear or outer portions of its longitudinal edges with forwardly or inwardly facing shoulders 28, these shoulders being formed by making the rear or outer ends of these plates wider than the front or inner parts thereof.

At opposite flat sides of the ends of the two sets of friction plates are arranged two pairs of wedge plates 29 and 30, members of each pair being arranged transversely opposite each other and engaging their inner longitudinal flat sides with the adjacent friction plates to produce a variable pressure upon the same and cause them to engage each other with varying degrees of friction and thus resist relative longitudinal movement of the same accordingly. The members of each pair of wedge plates are coupled with one of the thrust heads so as to be compelled to move lengthwise therewith most of the time and also to produce a wedging action of each thrust head against the respective pair of wedge plates at the corresponding end of the sets of friction plates during the forward or inward movement of the thrust head and thereby not only move the respective wedge plates forwardly or inwardly, but also press the same transversely inwardly so that the friction plates are pressed together and engage each other with increased frictional contact. This is preferably effected by providing the outer side of each wedge plate with a laterally projecting rib 31, the rear or outer side of which has an inclined face 32, the two inclines of the companion wedge plates at the same end of the draft gear diverging forwardly or inwardly, and engaging respectively with the forwardly or inwardly diverging inclined faces 26 of the respective thrust head, as shown in Figures 1 and 2. On its front or inner side the rib 31 of each wedge plate is provided with an inclined face 33, these faces of the companion wedge plates being so arranged that they converge forwardly or inwardly.

Surrounding each pair of wedge plates and the adjacent end of the two sets of intercalated friction plates is a thrust member or spring seat 34 which has the form of an oblong frame and the opening 35 of which receives the adjacent pair of wedge plates and the parts of the friction plates which are arranged between these wedge plates, as best shown in Figures 1, 2, 3, 4 and 11. The vertical inner edges of each of these thrust members or spring seats are provided with inclined faces 36 which diverge rearwardly or outwardly and engage respectively with the forwardly or inwardly converging inclined faces 33 on the adjacent wedge plates, so that a wedging engagement is produced between these parts upon effecting a relative longi-

tudinal movement of the same. On its upper and lower horizontal edges, each of the thrust members or spring seats is provided with horizontal tappets or shoulders 37, 37 which project rearwardly or outwardly into the opening 25 of the adjacent thrust head along the upper and lower sides of the adjacent end of the two sets of intercalated friction plates and adapted to engage with the forwardly or inwardly facing shoulders 28 at the rear or outer end of one of these sets, as shown in Figures 3 and 4. The forward or inward movement of each of the thrust members or spring seats 34 is effected by engagement therewith of the ribs 31 on the adjacent wedge plates during the forward or inward movement of the latter. The outward return or backward movement of each thrust member or spring seat is effected by spring pressure during a normal relaxation of the draft gear or shock absorber but for the purpose of compelling each of these thrust members and the wedge plates and friction plates associated therewith to move longitudinally backward or outward therewith at certain times, coupling means are provided which preferably consist of coupling or stop hooks 38 arranged on the upper and lower edges of the horizontal parts of the thrust member or spring seat and projecting rearwardly or outwardly therefrom so that the inwardly or forwardly projecting beaks or bills 39 form forwardly or inwardly facing shoulders 40 which are adapted to be engaged by rearwardly or outwardly facing shoulders or stops 41 formed on the front or inner edges of the opposite vertical sides of the respective thrust head, as shown in Figures 3 and 4.

The numeral 42 represents a thrust spring or main wedge spring which is preferably of helical form and surrounds the central parts of the friction plates and the inner or front ends of the wedge plates and bears at its opposite ends against the opposing flat faces 43 on the front or inner sides of the thrust members around the openings 35 thereof, as shown in Figures 1 to 4.

Resilient means are provided which operate constantly to move the thrust heads and the followers with which they engage outwardly, rearwardly or apart from each other for the purpose of releasing the draft gear or shock absorber. In the preferred form of these means, as shown in the drawings, the same comprise two helical releasing springs 44 which are arranged lengthwise on horizontally opposite sides of the main or thrust spring 42 and each of these releasing springs passing near its opposite ends through openings 45 formed in the corresponding ends of the thrust members 34 so as to form a guide and support for the latter. At its opposite ends, each of the releasing springs 44 bears against seats 46 formed on the corresponding portions of the front or

inner sides of the two thrust heads 23, 24, as shown in Figures 1 and 2.

The thrust heads 23, 24 are prevented from separating an undue extent when the draft gear is removed from the car by means which preferably comprise two tie rods 47, each of which extends lengthwise through one of the releasing springs 44 and openings 48 in the corresponding parts of the two thrust heads and is provided at opposite ends with shoulders 49, 50 which face forwardly or inwardly and engage with the rear or outer sides of the thrust heads 23, 24 this tie rod being preferably constructed in the form of a bolt, the head and nut of which form the shoulders 49 and 50 just referred to. The rear or outer sides of the thrust heads 23, 24 are provided with recesses 51 which receive the shouldered ends of the tie rods and permit these shouldered ends to partake of a limited longitudinal movement relatively to the thrust heads 23 and 24 without interference with the adjacent followers 16 and 17.

The movement of the thrust heads and followers forwardly toward each other is limited by positive means so as to prevent the shock absorber from being overloaded when subjected to a load beyond the capacity of the shock absorber. This is accomplished in the present instance by the use of a plurality of stop members 52 which are constructed in the form of solid rods or posts and arranged lengthwise along different parts circumferentially of the draft gear. In the preferred form two of such stop rods or posts 52 are arranged on opposite sides of each of the releasing springs 44 adjacent to the outer side of the thrust or wedge spring 42, each of these stop rods or posts passing near its opposite ends loosely through guide openings 53 formed in the marginal parts of the thrust members or spring seats 34, and also adapted to be engaged at its opposite ends by forwardly or inwardly facing shoulders or abutments 54 arranged on the adjacent marginal parts of the corresponding sides of the two thrust heads 23, 24, as best shown in Figures 1 to 4.

Each of these stop rods or posts is of less length than the distance between the corresponding shoulders 54 of the two thrust heads when the latter are separated to their maximum extent when the draft gear or shock absorber is in its fully released condition. This difference between the length of the stop rods and the distance between the shoulders 54 of the two thrust heads represents the amount of movement which the two thrust heads can effect toward each other when closing the shock absorber, and when this has been exhausted the stop shoulders 54 of the two thrust heads engage with opposite ends of the several stop rods 52 and render the draft gear practically solid.

Each of the stop rods 52 floats freely in the guide openings 53 of the thrust member 34 and is capable of moving lengthwise therein in either direction depending upon which ever thrust head is moved forwardly or inwardly.

- In order to adapt the intercalated friction plates generally to the shape of the space within the main thrust or wedge spring 42 those plates of both sets which are arranged in the central part of this space are made of the same width throughout from the shoulders 28 at the rear or outer ends thereof up to the front or inner ends of these plates, as shown in Figure 8, whereby these plates can be made of approximately maximum width and thus ensure a comparatively large frictional area contact between the wedge plates in the center of the mass of plates, whereby a large resisting effect is obtained when these plates are slid relatively to each other. Those plates of both sets, however, which are arranged adjacent to the outer or lateral sides of the mass of plates are made somewhat narrower on the front or inner parts thereof, as shown at 55 in Figure 5, so as to permit these plates to occupy the comparatively narrow space within the main thrust or wedge spring adjacent to the inner sides of the wedge plates or shoes 29, 30, as shown in Figure 7, thereby permitting of utilizing the space within the spring to greater advantage and increasing the capacity of the shock absorber accordingly.
- In order to facilitate assembling of the parts of the absorber and prevent the wedge plates from slipping forwardly through the thrust members 34 at this time, each of the wedge plates is provided on the rear or outer parts of its longitudinal edges with laterally projecting stop lugs or shoulders 56 which are adapted to engage the rear or outer stop faces or shoulders 37 on the respective thrust member or spring seats, this relative position of these parts being shown in Figures 3 and 4. These lugs also serve to guide the wedge plates and keep the same centrally within the main or thrust spring and in proper engagement with the outermost friction plates inasmuch as the side ends of these lugs are arranged close to and are adapted to engage with the inner vertical sides of the openings 25 in the thrust heads, as shown in Figures 3 and 4.
- The front or inner sides of the thrust members are provided with curved centering ribs 57 which engage with the periphery of the thrust spring at the ends thereof and hold the same against lateral displacement relatively to the thrust members.

The operation of this draft gear or shock absorber is as follows:

When the several members of the shock absorber are fully assembled and placed in the draft rigging of the car, the main thrust

or wedge spring and release springs are under an initial compression in the fully released or open position of these parts. The tie rods serve to limit the relaxation or opening movement of the shock absorber and also serve to hold the several parts together as a complete unit.

If a load is now applied to either or both of the followers and the thrust heads 23 and 24 engaging against the inner front sides thereof sufficient to overcome the initial tension of the springs of the shock absorber, these thrust heads and followers will be first forced one toward the other lengthwise of the gear, independently of the friction plates, thereby compressing the main thrust or wedge spring and the release springs. The thrust or wedge spring at this time creates a pressure against the thrust members or spring seats in a rearward outward direction toward both followers. The thrust members or spring seats exert a backward or outward pressure against the wedge plates through the medium of the cooperating inclined surfaces 33 and 32 of the wedge plates and thrust members 34. This produces a wedging action of the thrust members 34 against the wedge plates whereby the latter are pressed transversely inwardly against opposite sides of the two sets of wedge plates, whereby an increased pressure is produced between the cooperating surfaces of the friction plates. During the continued forward or inward movement of one follower toward the other, the front or inner sides of the followers engage the rear or outer ends of the friction plates so that thereafter one set of friction plates moves forwardly or inwardly with the movable follower. Increased frictional resistance is offered against such sliding movement due to the increased lateral pressure of these friction plates against one another by reason of the wedging action of the thrust heads and thrust members 34 against the wedge plates 29 and 30. This frictional resistance increases in the same measure as the thrust heads approach each other so that a gradually increasing friction resistance is offered to closing movement of the gear. The limit of such movement is reached when the front or inner abutment surfaces 54 of both thrust heads 23 and 24 engage with the opposite ends of the stop rods or posts 52 at which time the shock absorber is solid and no further closing or cushioning effect of the same occurs, thereby preventing injury to any parts of the absorber in the event that a shock or blow is given to the absorber which is in excess of the capacity for which the particular shock absorber is intended.

If now the load on the followers and thrust heads is released or is lessened below the capacity of the release springs, the latter will force the thrust heads or wedge casings 23 and 24 and the followers engaging there-

with backwardly or outwardly. The main thrust or wedge spring also forces the thrusting springs interposed between said thrust members or spring seats 34 backwardly or outwardly a like amount until the shoulders 37 on the spring seats come in contact with the shoulders 28 on the friction plates. The main thrust or wedge spring 42 then tends to retract or move the friction plates backwardly or outwardly while the release springs 10 tend to release the wedging engagement of the thrust heads 23 and 24 from the rear or outer inclined surfaces 32 on the wedge plates. When this wedging action is sufficiently relieved the main thrust or wedge spring moves the friction plates backwardly or outwardly which tends to force the thrust heads and followers apart or backwardly or outwardly inasmuch as there is more pressure exerted by the main or wedge spring than is necessary to bring the friction plates backwardly or outwardly to their released position. This releasing movement of the draft gear continues until the rear or outer faces of the thrust heads 23 and 24 engage with the shoulders 49 and 50 on the tie rods at which time the shock absorber is in its fully opened or released position but still under the initial tension which has been put into the same when assembling the parts. The engagement of the shoulders or stops 37 on the thrust members is effected while the latter move backwardly or outwardly a sufficient extent for this purpose independently of the friction plates but thereafter the thrust members and friction plates move backwardly or outwardly together until the gear is fully opened. During this opening movement the front or inner sides of the followers are also again disengaged from the rear or outer ends of the friction plates.

I claim as my invention:

1. A shock absorber comprising thrust heads movable lengthwise relatively to each other, wedge plates engaging with said thrust heads, intercalated friction plates adapted to be pressed together by said wedge plates, thrust members having wedging engagement with said wedge plates, a thrust spring interposed between said thrust members, releasing springs interposed between said thrust heads, stop rods arranged in pairs on said thrust members and adapted to be engaged by said thrust heads for limiting the closing movement of the absorber and means for causing the friction plates to move relative to each other on compression and on release.
2. A shock absorber comprising thrust heads movable lengthwise relatively to each other, wedge plates engaging with said thrust heads, intercalated flat friction plates adapted to be pressed together by said wedge plates, thrust members having wedging engagement with said wedge plates, and having guide openings, a thrust spring inter-
3. A shock absorber comprising thrust heads movable lengthwise relatively to each other, wedge plates having wedging engagement with said thrust heads, intercalated plates to move relative to each other on compression and on release.
4. A shock absorber comprising thrust heads movable lengthwise relatively to each other, wedge plates engaging with said thrust heads, a single column of intercalated friction plates between said wedge plates adapted to be pressed together by said wedge plates, thrust members having wedging engagement with said wedge plates, a thrust spring interposed between said thrust members, releasing springs interposed between said thrust heads, stop rods mounted on said thrust members and adapted to be engaged by said thrust heads for limiting the closing movement of the absorber and means for causing the friction plates to move relative to each other on compression and on release.
5. A shock absorber comprising thrust heads movable lengthwise relatively to each other, wedge plates engaging with said thrust heads, intercalated flat friction plates adapted to be pressed together by said wedge plates, thrust members having wedging engagement with said wedge plates and having a plurality of openings, a thrust spring interposed between said thrust members, releasing springs passing through said openings and interposed between said thrust heads and means for causing the friction plates to move relative to each other on compression and on release.
6. A shock absorber comprising a plurality of sets of intercalated flat friction plates, wedge plates engaging with opposite lateral sides of said sets of friction plates, thrust heads movable relatively to each other and provided with openings receiving said friction plates and wedge plates and engaging with said wedge plates, thrust members having openings which receive said friction plates and wedge plates and having

wedging engagement with the latter, a thrust spring surrounding the friction plates and wedge plates and engaging with said thrust members, releasing springs interposed between said thrust heads and means for causing the friction plates to move relative to each other on compression and on release.

7. A shock absorber comprising a plurality of sets of intercalated flat friction plates,

- 10 wedge plates engaging with opposite lateral sides of said sets of friction plates, thrust heads movable relatively to each other and provided with openings receiving said friction plates and wedge plates and having wedging engagement with said wedge plates, thrust members having openings which receive said friction plates and wedge plates and having wedging engagement with the latter, a thrust spring surrounding the friction plates and wedge plates and engaging with said thrust members, releasing springs interposed between said thrust heads.
- 15
- 20

8. A shock absorber comprising a plurality of sets of intercalated friction plates,

- 25 wedge plates engaging with opposite lateral sides of said sets of friction plates, thrust heads movable relatively to each other and provided with openings receiving said friction plates and wedge plates and engaging with said wedge plates, thrust members having openings which receive said friction plates and wedge plates and having wedging engagement with the latter, and having stop shoulders which project rearwardly into the openings of said thrust head and adapted to engage with forwardly facing shoulders on said friction plates, a thrust spring surrounding the friction plates and wedge plates and engaging with said thrust members, releasing springs interposed between said thrust heads and means for causing the friction plates to move relative to each other on compression and on release.
- 30
- 35
- 40

9. A shock absorber comprising a plurality of sets of intercalated friction plates,

- 45 wedge plates engaging with opposite lateral sides of said sets of friction plates, thrust heads movable relatively to each other and provided with openings receiving said friction plates and wedge plates and engaging with said wedge plates, thrust members having openings which receive said friction plates and wedge plates and having wedging engagement with the latter, and having forwardly facing shoulders adapted to engage with rearwardly facing shoulders on said thrust heads, a thrust spring surrounding the friction plates and wedge plates and engaging with said thrust members, releasing springs interposed between said thrust heads and means for causing the friction plates to move relative to each other on compression and on release.
- 50
- 55
- 60

10. A shock absorber comprising a plurality of sets of intercalated friction plates,

wedge plates engaging with opposite lateral sides of said sets of friction plates, thrust heads movable relatively to each other and provided with openings receiving said friction plates and wedge plates and engaging with said wedge plates, thrust members having openings which receive said friction plates and wedge plates and having wedging engagement with the latter, and having stop shoulders which project rearwardly into the openings of said thrust head and adapted to engage with forwardly facing shoulders on said friction plates, a thrust spring surrounding the friction plates and wedge plates and engaging with said thrust members, releasing springs interposed between said thrust heads and said wedge plates having laterally projecting lugs at their rear ends which are arranged within the openings of said thrust heads and in rear of the shoulders of said thrust members and means for causing the friction plates to move relative to each other on compression and on release.

11. A shock absorber comprising a plurality of sets of intercalated friction plates,

wedge plates engaging with opposite lateral sides of said sets of friction plates, thrust heads movable relatively to each other and provided with openings receiving said friction plates and wedge plates and engaging with said wedge plates, thrust members having openings which receive said friction plates and wedge plates and having wedging engagement with the latter, a thrust spring surrounding the friction plates and wedge plates and engaging with said thrust members, and releasing springs interposed between said thrust heads, the inner ends of the friction plates in the central part of the thrust spring being comparatively wide and the friction plates adjacent to opposite sides of said thrust spring having their inner parts made comparatively narrow, said elements being organized for causing the friction plates to move relative to each other on compression and on release.

12. A shock absorber comprising a plurality of sets of intercalated friction plates,

wedge plates engaging with opposite lateral sides of said sets of friction plates, thrust heads movable relatively to each other and provided with openings receiving said friction plates and wedge plates and engaging with said wedge plates, thrust members having openings which receive said friction plates and wedge plates and having wedging engagement with the latter, a thrust spring surrounding the friction plates and wedge plates and engaging with said thrust members, and releasing springs interposed between said thrust heads, the inner sides of said thrust heads being provided with centering ribs which hold the thrust spring against lateral displacement relatively thereto, said elements being organized for caus-

ing the friction plates to move relative to each other on compression and on release.

13. A shock absorber comprising a plurality of sets of intercalated flat friction plates, wedge plates engaging with opposite lateral sides of said sets of friction plates, thrust heads movable relatively to each other and provided with openings receiving said friction plates and wedge plates and engaging with said wedge plates, thrust members having openings which receive said friction plates and wedge plates and having wedging engagement with the latter, a thrust spring surrounding the friction plates and wedge plates and engaging with said thrust members, releasing springs interposed between said thrust heads, and followers adapted to engage the outer ends of said friction plates, said elements being organized for causing the friction plates to move relative to each other on compression and on release.

14. A shock absorber comprising thrust heads movable lengthwise relatively to each other, wedge plates engaging with said thrust heads, intercalated flat friction plates adapted to be pressed together by said wedge plates, thrust members having wedging engagement with said wedge plates, a thrust spring interposed between said thrust members, releasing springs interposed between said thrust heads, stop rods mounted on said thrust members and adapted to be engaged by said thrust heads for limiting the closing movement of the absorber, and followers adapted to engage the outer ends of said friction plates, said elements being organized for causing the friction plates to move relative to each other on compression and on release.

15. A shock absorber comprising a plurality of sets of intercalated friction plates, followers adapted to engage the outer ends of said friction plates, wedge plates engaging with the outer lateral sides of said sets of friction plates and each having inner and outer inclined faces, heads engaging the inner sides of said followers and each having inclined faces engaging the outer inclined faces of the wedge plates at one end of said friction plates, thrust members each having outer inclined faces engaging with the inner inclined faces of the wedge plates at one end of said friction plates, a wedge spring engaging the inner side of said thrust members and surrounding said friction plates, releasing springs engaging with the inner sides of said heads and passing through said thrust member, tie rods extending through said releasing springs and having shoulders at their ends which bear against the outer side of said heads, and stop rods mounted on said thrust members and adapted to engage their opposite ends with the inner side of said heads, said heads having outer shoulders, said thrust members having retaining hooks

adapted to engage said shoulders, and the friction plates of each set having inwardly facing shoulders adapted to engage an outwardly facing shoulder on one of said thrust members.

16. In a friction shock absorbing mechanism, the combination with a group of intercalated, relatively movable, longitudinally disposed friction plates; wedge friction shoes at the opposite ends of said plates, said shoes being disposed at opposite sides of the group of plates; spring resistance means exterior of said group of plates; spring followers interposed between said spring resistance and the shoes at the opposite ends of the plates, said followers having means thereon engaging said plates for returning them to normal position; and relatively movable main followers having wedge means associated therewith, forcing said shoes toward the axis of the mechanism.

17. A draft gear comprising main followers relatively movable toward each other; a centrally disposed column composed of two sets of longitudinally extending flat friction plates having faces engaging each other, said plates being adapted for movement relatively to each other by said followers; means for restoring said friction plates to normal position after each compression of the gear; means at each end of said column coacting with said followers for pressing said plates into tight frictional engagement with each other during a compression stroke, and spring resistance elements including a spring encircling said friction plates for resisting the compression of said gear, and other spring means engaging said followers for moving the same outwardly longitudinally of the gear for releasing said last-named means, and for restoring said followers to normal release position upon the release of said gear.

18. A draft gear comprising a pair of followers, spring means engaging said followers for resisting compression of said gear, a centrally disposed column composed of a plurality of sets of intercalated flat friction plates which engage each other, and are movable lengthwise relatively to one another, pressing means including wedging shoes engaging the outermost plates, and a thrust member having wedging engagement with said shoes at opposite ends of said column for pressing said plates together during a compression stroke, and means including a spring resistance arranged externally of and surrounding said column for resisting the longitudinal movement of said plates during a compression stroke and to restore said plates to normal position after each compression of the gear.

19. A draft gear comprising a pair of followers, spring means engaging said followers for resisting compression of said gear, a cen-

trally disposed column composed of a plurality of sets of intercalated flat friction plates which engage each other and are movable lengthwise relatively to one another, pressing means at opposite ends of said column, a thrust member for engaging said pressing means for pressing said plates together during a compression stroke, a spring member surrounding said plates for resisting the longitudinal inward movement of said pressing means and thrust member, and means for restoring the plates to normal position after release.

20. A draft gear comprising a plurality of sets of intercalated flat friction plates, followers adapted to engage the outer ends of said sets of plates, wedge plates movable lengthwise with said followers and engaging with the outer sides of said friction plates, thrust members having wedging engagement with said wedge plates, a thrust spring surrounding said friction plates and engaging said thrust members, and means for returning the plates to normal or released position.

25. 21. A draft gear comprising a plurality of sets of intercalated flat friction plates, followers adapted to engage the outer ends of said sets of plates, wedge plates movable lengthwise with said followers and engaging with the outer sides of said friction plates, thrust members having wedging engagement with said wedge plates, a thrust spring surrounding said friction plates and engaging said thrust members, releasing spring means 30 interposed between said followers and arranged outside of said thrust spring, and means for returning the plates to normal or released position.

22. A draft gear comprising a plurality of sets of intercalated flat friction plates, followers adapted to engage the outer ends of said sets of plates, wedge plates movable lengthwise with said followers and engaging with the outer sides of said friction plates, thrust members having wedging engagement with said wedge plates, a thrust spring surrounding said friction plates and engaging said thrust members, releasing spring means interposed between said followers and arranged outside of said thrust spring, a tie rod extending through said releasing spring means and connecting said followers, and means for returning the plates to normal or released position.

55. 23. In a draft gear, a pair of followers, a single group of two sets of longitudinally movable intercalated flat friction plates between said followers, wedging means at each end of said gear at each side of said group 60 of plates for forcing said plates laterally inward during the compression of said gear, resilient means for resisting the compression of said gear, springs engaging said followers for resisting the compression of said gear and for separating said followers when said

gear is released after compression, and means separate from said followers for engaging one end of each set of plates for restoring the same to normal position after the release of said gear.

CERTIFICATE OF CORRECTION.

Patent No. 1,831,173.

Granted November 10, 1931, to

JOSEPH M. HALL.

It is hereby certified that error appears in the printed specification of the above numbered patent requiring correction as follows: Page 6, line 22, claim 7, after the word "heads" insert the words and means for causing the friction plates to move relative to each other on compression and on release; and that the said Letters Patent should be read with this correction therein that the same may conform to the record of the case in the Patent Office.

Signed and sealed this 22nd day of December, A. D. 1931.

(Seal)

**M. J. Moore,
Acting Commissioner of Patents.**
